Primary Examiner — Catherine S Posthauer

Assistant Examiner — Christine Marie Achen Zimmerman
(74) Attorney, Agent, or Firm — Birchwood IP(57) **CLAIM**

The ornamental design for a bottle cap, as shown and described.

DESCRIPTION

FIG. 1 is a front, top and right side perspective view of a

bottle cap, showing my new design;

FIG. 2 is a rear, bottom and left side perspective view

thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part

of the claimed design.

The broken lines represent parts of the article, as well as

boundaries of the claim. None of the broken lines form part
